CLAIM

The ornamental design for a shoe as shown and described.

DESCRIPTION

FIG. 1 is a side view of a shoe showing our new design; FIG. 2 is a front perspective view thereof; FIG. 3 is an opposite side front perspective view thereof; and, FIG. 4 is an opposite side view thereof.

The broken line showing of the four quadrilateral-shaped regions within the shaded area represent eyelets that form no part of the claimed design. The broken lines showing the thickness and the inside surface of tongue-surround panel forms no part of the claimed design. The broken lines immediately adjacent to the shaded area define the bounds of the claimed design and form no part thereof. The broken lines depicting the remainder of the shoe form no part of the claimed design.
